UNITED STATES PATENT OFFICE

132,562

DESIGN FOR A SHAMPOO PAN

Paula R. Keirle, St. Louis, Mo.

Application August 20, 1941, Serial No. 102,963

Term of patent 14 years

To all whom it may concern:

Be it known that I, Paula R. Keirle, a citizen of the United States, residing at the city of St. Louis, State of Missouri, have invented a new, original, and ornamental Design for a Shampoo Pan, of which the following is a specification, reference being had to the accompanying drawing, forming part thereof.

Fig. 1 is a perspective view of a shampoo pan showing my design;

Fig. 2 is a top plan view thereof;
Fig. 3 is an end elevational view thereof; and
Fig. 4 is a side elevational view thereof.

I claim:

The ornamental design for a shampoo pan, as shown.

PAULA R. KEIRLE.
